United States Patent

Des. 237,330
Patented Oct. 28, 1975

237,330

SEAT

Robert A. Skyer, Palatine, David S. Faust, Chicago, and
George E. Bowman, Country Club Hills, Ill., assignors
to International Harvester Company, Chicago, Ill.

Filed June 26, 1974, Ser. No. 483,204

Term of patent 14 years

Int. Cl. D6—01

U.S. Cl. D6—48

FIG. 1 -

FIG. 2 -

FIG. 1 is a 3/4 perspective view as seen from the right front of the seat embodying our new design;

FIG. 2 is a plan view thereof;

FIG. 3 is a side view thereof;

FIG. 4 is an elevation view thereof; and

FIG. 5 is a rear view thereof.

We claim:

The ornamental design for a seat, substantially as shown and described.
